DESIGN FOR A BOTTLE

Anthony B. Cassedy, Boston, Mass.

Application May 3, 1934, Serial No. 51,681

Term of patent 14 years

To all whom it may concern:

Be it known that I, Anthony B. Cassedy, a citizen of the United States of America, residing at Boston, in the county of Suffolk, Commonwealth of Massachusetts, have invented a new, original, and ornamental Design for a Bottle, of which the following is a specification, reference being had to the accompanying drawing, forming a part thereof.

In the drawing:

Fig. 1 is a top view illustrating my new design for a bottle.

Fig. 2 is a front view, and

Fig. 3 is a side view.

I claim:

The ornamental design for a bottle substantially as shown.

ANTHONY B. CASSEY.
